UNITED STATES PATENT OFFICE.

WILLIAM R. CONLEY, OF FAIRGROVE, MICHIGAN.

HAY-RACK.

SPECIFICATION forming part of Letters Patent No. 279,343, dated June 12, 1883.

Application filed October 30, 1882. (No model.)

To all whom it may concern:

Be it known that I, WILLIAM R. CONLEY, of Fairgrove, in the county of Tuscola and State of Michigan, have invented certain new 5 and useful Improvements in Hay-Racks; and I do hereby declare that the following is a full, clear, and exact description of the invention, which will enable others skilled in the art to which it appertains to make and use the same, 10 reference being had to the accompanying drawings, which form a part of this specification.

This invention relates to portable hay and grain racks for wagon-boxes; and the novelty consists in the construction and arrangement 15 of parts, as will be more fully hereinafter set forth, and specifically pointed out in the claim.

The object of the invention is to provide a cheap, simple, and efficient hay-rack, one which may be placed in or displaced out of operation by a single man, and one which may 20 be folded within small compass and be conveniently housed or packed.

To this end the invention consists in two frames or panels hinged or pivoted together, 25 and provided with square-faced recesses which rest upon the box of the wagon, while stops secured to either of the panels above the pivotal point serve to rest upon the portions of the opposite panel below the said pivots to 30 distribute the weight and give a firm, square bearing on the wagon-box. The front standard is removable, and the two panels are readily folded together, as will be shown.

The device is made of strong lumber; but 35 its construction is such that when completed its weight will allow its ready handling by a single person, and it may be folded and hung on pegs under shelter—a desideratum in agricultural pursuits.

40 The invention is fully illustrated in the accompanying drawings, which form a part of this specification, and in which—

Figure 1 is a perspective view of my invention open and ready for use; and Fig. 2, a 45 similar view of the device folded.

Referring to the drawings, A A represent arms, which, in connection with longitudinal boards A' A', form one of the panels; and B B represent similar arms, which, with the boards B' B', form the opposite panel. These 50 panels are pivoted, hinged, or movably connected together at c, and each of the arms A A and B B is provided with a bearing-shoulder, d, adapted to rest upon the upper edge of the wagon-box, while the feet of the several 55 arms abut against the sides and bottom of the box. From each of the arms A B extends a short stop, e, secured to each of the said arms above the pivot or hinge, and these stops project downward, their lower ends resting upon 60 the feet of the arms upon the opposite panel. These stops serve as fulcrums to equalize the load.

F represents the standard, the base of which operates in a recess or box, f, formed for its 65 reception, and a cross-bar, f', serves to give it strength and steadiness.

The operation of the device is obvious.

Having thus described the invention, what I claim, and desire to secure by Letters Patent 70 of the United States, is—

The herein-described folding hay-rack, consisting of the arms A B, notched at d, the boards A' B', secured to said arms to form two panels, hinged or pivoted together at c, the 75 stops e, fastened in contiguity to the notches d, and the removable standard F, having cross-bar f', all constructed, arranged, combined, and operating in relation to a wagon-box, as and for the purpose shown and set forth. 80

In testimony that I claim the foregoing as my own I have hereunto affixed my signature in presence of two witnesses.

WILLIAM R. CONLEY.
